Primary Examiner — Cathron C Brooks*Assistant Examiner* — Andrew T Nemeth(74) *Attorney, Agent, or Firm* — Weaver Austin Villeneuve & Sampson LLP(57) **CLAIM**

We claim the ornamental design for a display screen with a graphical user interface, as shown and described.

DESCRIPTION

FIG. 1 depicts a front view of a display screen with a graphical user interface showing a first embodiment of an instrument status bar of the design.

FIG. 2 depicts a front view of a display screen with a graphical user interface showing a second embodiment of an instrument status bar of the design; and,

FIG. 3 depicts a front view of a display screen with a graphical user interface showing a third embodiment of an instrument status bar of the design.

The broken lines shown in the Drawings represent portions of the display screen and/or graphical user interface that form no part of the claimed design.

1 Claim, 3 Drawing Sheets(56)
